FORREST H. MARTELL, OF MILWAUKEE, WISCONSIN, ASSIGNOR TO S. M. SIESEL CO., OF MILWAUKEE, WISCONSIN, A CORPORATION OF WISCONSIN

STRUCTURAL STEEL WRAPPING SPACER

Application filed March 14, 1930. Serial No. 435,814.

This invention relates to improvements in structural steel wrapping spacers.

It is one of the objects of the present invention to provide a spacer for structural steel wrapping which is of a standard size and may be used with all widths of flanges and with all thicknesses of flanges of structural steel ordinarily encountered, thereby eliminating the necessity of having on hand 5 and sorting various sized spacers for use on steel members of different sizes during construction work.

A further object of the invention is to provide structural steel wrapping spacers which 15 may be applied on steel members in any desired spacing arrangement, depending upon the specifications.

Wrapping devices now on the market are constructed so that the wrapping wire directly 20 engages the lower flange of a structural steel beam, and in the event of any bending the lower flange of the beam is where the greatest stress ordinarily occurs, and if the wrapping wire adjacent the lower flange 25 of the beam is not completely encased in the concrete, it will not withstand the maximum amount of stresses.

A further object of the invention is to provide a structural steel wrapping spacer which 30 will overcome the above disadvantages by spacing or holding wire away from the lower flange of the beam out into the middle of the cementitious mass, whereby the wrapping wire is thoroughly encased in concrete and 35 will develop its fullest strength.

A further object of the invention is to provide a structural steel wrapping spacer and wrapping wherein the latter, by being secured over the top flange of the beam, or on opposite 40 sides of the spacer, gives added strength to the beam, inasmuch as the wrapping engages directly or indirectly four edge portions of the steel member and will therefore bind and be prevented from sliding out of position, and the spacer per se, when encased in the cementitious mass, will assist in holding 45 the latter in place around the structural steel member.

A further object of the invention is to provide a structural steel wrapping spacer and

wrapping therefor, which, when applied to beams in concrete construction work, will not prevent the free flow of cementitious material around the beams.

A further object of the invention is to provide a structural steel wrapping spacer which may be erected very easily and quickly, which is strong and durable, which is inexpensive to manufacture, and which is well adapted for the purposes described. 55

With the above and other objects in view, the invention consists of the improved structural steel wrapping spacer and its parts and combinations as set forth in the claims, and all equivalents thereof. 60

In the accompanying drawings in which the same reference characters indicate the same parts in all of the views: 65

Fig. 1 is a cross-sectional view through a horizontally disposed structural steel beam 70 having the improved spacers applied thereto and wrapping engaging the spacers and the beam, with the beam and spacers and wrapping shown encased in a cementitious mass molded thereabout; 75

Fig. 2 is a fragmentary perspective view of the upper flange of a steel beam showing how the wrapping engages said upper flange; 80

Fig. 3 is a detail perspective view of a spacer; 85

Fig. 4 is a detail perspective view on a smaller scale showing a pair of spacers joined by a rod; and

Fig. 5 is a cross-sectional view through a vertical steel beam and molded concrete thereabout, showing the application of the improved spacers and wrapping to a vertical beam. 90

Referring now more particularly to the drawings, it will appear that the wrapping spacer, designated by the numeral 8, is formed of a length of wire of a suitable gauge, or other similar material, which is yieldable or bendable, and said wire is bent to form two laterally opposed clip portions 9, 95 and below the clip portions, are doubled over rearwardly turned portions 10 which extend outwardly and are joined by a transverse portion 11 formed with an intermediate inwardly curved or recessed portion 12. 100

A structural steel I-beam 13, disposed horizontally, as in ceiling constructions, is shown in Figs. 1 and 2 and the improved spacers 8 are adapted to be applied to the opposite lower flanges 14 thereof in the manner shown in Fig. 1 and said spacers, on each lower flange, may be spaced apart longitudinally of the beam at any convenient distance. The clip portions 9 of each spacer are yielding and engage a flange portion 14 of the I-beam and are held on said flange by the tension of the clip portions. The spacer members may be further secured to soffit or form boards 15 by staples 16 engaging lower portions of the spacers and extending into the form boards. With pairs of spacers disposed as shown in Fig. 1 on opposed sides of the lower flanges of the I-beam, a wrapping wire may be supported thereby and spaced from the lower flange of the I-beam. Said wrapping wire 17 is extended below the lower flanges of the I-beam and engages in the recesses 12 of the transverse portions 11 of the two opposed spacers. The wrapping wire 25 is then bent upwardly on both sides and is extended over and around the upper flange 18 of the I-beam, and the opposite end portions of the wrapping wire are then wrapped or bent around opposite portions of the upper flange and against lower surfaces thereof, as clearly shown in Figs. 1 and 2. As shown in Fig. 4, a number of spacers 8 may be suitably joined together at spaced intervals in a longitudinal line by a longitudinally extending wire or strip 19 which is welded to lower corner portions of the clip portions 9 of the spacer, as at 20. When a number of spacers are so joined they may be quickly applied to one side of the lower portion of an I-beam and will be correctly spaced and will be held in correct spaced relation.

After the application of the spacers to the lower flanges of a horizontal I-beam, and after the wrapping wire has been engaged by the spacers as described and bent about the upper flange of the I-beam, cementitious material, as indicated by the numeral 21, may be poured into the soffit or form boards, surrounding the beam and spacers and wrapping wire, as shown clearly in Fig. 1. When the concrete has set, the spacing wire will be embedded in the cementitious mass and will be firmly supported spacedly from the lower flanges of the I-beam, giving to the I-beam the maximum amount of strength.

Fig. 5 illustrates the manner in which the improved spacers are applied to a vertical I-beam such as is used in forming a vertical column. In this form, the spacers are clipped onto the flanges 22 of the vertical I-beam 13' and are positioned in vertically spaced apart arrangement on all of the flanges. The wrapping wire 17' is then bent about the beam and spacers in a substantially squared form and is engaged at each corner portion

within a recess 12 of a spacer. The wrapping wire so disposed is prevented from slipping and is held by the spacers outwardly of and away from all portions of the flanges of the I-beam. Therefore, when the cementitious material 21 is poured into the form 15' it will surround or encase the I-beam, the spacers and the wrapping wires, and all portions of the wrapping wires will be encased in a substantial mass of concrete and will be spaced away from the flanges of the beam.

From the foregoing description it will be seen that the improved spacers, when mounted on flanges of structural steel beams or columns, securely support wrapping wire for the beams or columns and hold the wrapping wires in the proper spaced relation outwardly of the surface of the beams or columns, whereby the wrapping wires become embedded in the cementitious mass poured around the beam or column and the greatest possible strength is secured. The improved spacers and wrapping applied thereto do not in any way restrict the free flow of cementitious material around the steel members during the construction work, and the spacers and wrapping are of such nature that they may be easily and quickly applied to the structural steel beams or columns. Furthermore, the improved spacers and wrapping therefor are of simple and novel construction and are well adapted for the purposes set forth.

What I claim as my invention is:

1. In a building construction, a flanged beam, a pair of metallic spacing members engaging opposite sides of a flange thereof, each spacing member having a yieldable clip portion and an offset recessed portion, a separate wrapping element surrounding the beam and engaging the offset recessed portions of the spacing members and supported by said members spacedly, outwardly of all portions of said flange, and cementitious material surrounding the beam encasing the same, the spacing members and the wrapping element.

2. A structural steel wrapping spacer, comprising duplicate, spaced-apart parallel members, each consisting of a yielding, U-shaped engaging clip with the lower arm of the clip bent rearwardly upon itself, and a transverse member joining the outer ends of the rearwardly bent arm portions of the duplicate clips, said transverse member having an intermediate recess to receive therein a portion of a separate wrapping element.

In testimony whereof I affix my signature.

FORREST H. MARTELL.
